HOT AIR SUPPLY TO INTAKE MANIFOLDS

Filed Aug. 3, 1922

FIG. 2.

FIG. 3

FIG. 4

FIG. 5.

Frederick W. Schramm,

INVENTOR.

BY

Frank A. Cutler,

ATTORNEY.

UNITED STATES PATENT OFFICE.

FREDERICK W. SCHRAMM, OF SPRINGFIELD, MASSACHUSETTS.

HOT-AIR SUPPLY TO INTAKE MANIFOLDS.

Application filed August 3, 1922. Serial No. 579,352.

To all whom it may concern:

Be it known that I, FREDERICK W. SCHRAMM, a citizen of the United States of America, and a resident of Springfield, in the county of Hampden and State of Massachusetts, have invented a new and useful Hot-Air Supply to Intake Manifolds, of which the following is a specification.

My invention relates to improvements in attachments for the intake or inlet manifolds of internal-combustion engines, and consists generally of a particular form of gasket for the coupling between the carburetor and the inlet manifold of the engine, tubular members which replace the bolts usually provided for such coupling, and opening through said gasket into the manifold passage, a certain peculiar distributor mounted on said tubular members and opening into the same, a valve for said distributor, means to operate said valve from and with the member by means of which the needle-valve of said carburetor is manipulated by the operator at a point behind the dashboard of the machine, and a tubular connection between said distributor and the outside of the exhaust pipe of said engine, together with such other parts and members as may be necessary or desirable in order to render the attachment complete in every respect, all as hereinafter set forth.

It is well known that the exhaust pipe of an internal-combustion engine becomes very hot and radiates a large amount of heat, and the primary object of my invention is to provide such engine with comparatively simple and inexpensive means for heating with such hot air the combustible mixture discharged from the carburetor into the inlet manifold, such hot air being introduced directly into such mixture, whereby the quality of said mixture is improved, the speed and power of the engine increased, and a saving in fuel effected.

Another object is to produce an attachment of this character which can be readily attached to the coupling between the carburetor and inlet manifold of the engine, and arranged in effective relation to the exhaust pipe of said engine.

A further object is to control the passage through the device of the hot air from the exterior of the exhaust pipe, through the me-

dium of the same rod that is provided for controlling or operating the needle-valve of the carburetor.

Other objects and advantages will appear in the course of the following description.

I attain the objects and secure the advantages of my invention by the means illustrated in the accompanying drawings, in which—

Figure 1 is a top plan and partial section of a hot-air supply for inlet manifolds, which embodies a practical form of my invention; Fig. 2, a reduced, central, longitudinal section through the distributor; Fig. 3, a vertical section taken on lines 3—3 in Fig. 1, following the general directions indicated by lines 3'—3' in Fig. 2, and on lines 3"—3" in Fig. 1, looking in the direction of the associated arrows; Fig. 4, a plan of the special gasket used in the attachment, and, Fig. 5, a detail illustrating the manner in which connection or contact is made with the exhaust pipe.

Similar reference characters designate similar parts throughout the several views.

In the first two views a fragmentary portion, in section and elevation respectively, of an inlet manifold is represented at 1; the adjacent terminal portion, also in section and elevation respectively, of a carburetor at 2; and part of a rotatable rod at 4 for the adjustment of the needle-valve (not shown) of said carburetor. A fragment of an exhaust pipe appears at 5 in Fig. 3, and the same is shown in cross section in Fig. 5. These parts and members are old and well known. The carburetor 2 and the manifold 1 are provided at adjacent ends with coupling flanges 6 as usual, which flanges extend outwardly from opposite sides of said carburetor and manifold, and are perforated to receive bolts by means of which such flanges are secured together with a gasket between. A gasket is here represented at 7, but the same differs from the gasket commonly used, as explained below.

The gasket 7, Fig. 4, has a large central opening 8 therethrough with oppositely-disposed extensions or slots 9—9, such slots communicating at their inner ends with said opening, and projecting outwardly into the longitudinal or horizontal parts or arms of said gasket. The opening 8 is of the same

diameter as that of the adjacent terminals of the passages in the carburetor 2 and the manifold 1, and said passages communicate with each other through said opening. The 5 width of each slot 9 in the gasket 7 corresponds with the diameter of the companion bolt openings through the flanges 6 on either side of the central, vertical plane of the carburetor and manifold, with which 10 openings the outer end of said slot registers when said gasket is properly arranged between said flanges.

The flanges 6 are secured together and the gasket 7 tightly compressed between them 15 and the adjacent ends of the carburetor 6 and manifold 1, by means of a pair of horizontal, tubular members or tubes 10. The tubes 10 have, adjacent to their inner or rear terminals, shoulders 11—11 which abut the 20 front face of the flange 6 on the manifold 1, and the terminal portions of said tubes back of said shoulders pass through the bolt openings in both flanges 6 and through the gasket slots 9, and project beyond the back side of 25 the carburetor flange to receive nuts 12—12, such terminal portions being externally screw-threaded for that purpose. The nuts 12 are screwed up tightly on the protruding, rear terminals of the tubes 10, against the 30 back side of the carburetor flange 6. Thus the flanges 6 are securely held together with the gasket 7 between by the shoulders 11 and the nuts 12, and the tubes 10 are firmly supported and held in place. The rear end of 35 each tube 10 is closed by a plug 13. Orifices 14—14 are located in adjacent sides of the tubes 10 in position to register with the gasket slots 9, so that passageways are formed, from the passages in said tubes to the passage 40 in the manifold 1, through the orifices 14 and slots 9 and the opening 8, as clearly shown in Fig. 1.

Each tube 10 is further provided with a shoulder 15 which is located adjacent to the 45 forward end thereof. Mounted on the forward terminal portions of the tubes 10 is a member which I term a distributor 16, such distributor having transverse openings 50 17—17 in the base portions thereof to receive said terminal portions of said tubes. The interior of the passage in each tube 10 is screw-threaded adjacent to the forward end of such passage to receive an adjusting screw 55 18. The screws 18 are provided with nuts 19 by means of which said screws are locked after adjustment, and the distributor 16 is held securely in place on the tubes 10, since 60 said nuts 19 bear against the front side of said distributor and force the latter against the shoulders 15. There are two oblique passages 65 20 in the distributor 16 which passages connect at their bottom ends with the openings 17 below, and there is an orifice 21 in the top of each tube 10 so located that one of said passages connects at the bottom with

said orifice, thus establishing communication between said passage and the interior of said tube.

The distributor 16 is provided just below the top in the transverse center with a front projection 22 and a rear projection 23. There is a horizontal passage 24 which extends from the longitudinal, central plane of the distributor 16 forwardly through the projection 22, and a horizontal passage 25 of larger diameter in the projection 23, said passages being in line with each other. The rear end of the passage 25 is closed by a plug 26, and a valve-seat 27 is formed at the forward terminal of said passage where the same joins the passage 24. Two oppositely-disposed, longitudinally-extending passages 28 connect the passages 20 at the top with the inner or rear end of the passage 24. 75

A valve 29 is located in the passage 25 and adapted to close the valve-seat 27. The valve 29 has a stem 30 which extends rearwardly from said valve through the plug 26 and beyond the same. A spiral spring 31 encircles the valve-stem 30 between the plug 26 and the valve 29, and normally retains 80 said valve on the valve-seat 27.

The adjusting rod 4 is provided with an arm 32, and a spiral spring 33 has one end connected with said arm and the other end connected with the valve-stem 30. The spring 33 when contracted is weaker than the spring 31, but the relative strengths of 90 said springs are such that, when said first-named spring is expanded, the resistance of said second-named spring is overcome, and the valve-stem 30 is actuated rearwardly, thus moving the valve 29 off of the valve-seat 27. The construction and arrangement of parts are 95 such that these actions take place when the rod 4, with the arm 32, is partially rotated in the direction of the encircling arrow. When the rod 4 with its arm is then actuated in the opposite direction, the force of 100 the spring 33 is decreased to an extent which enables the spring 31 to move the valve 29 into closed position. The extent to which the valve 29 is opened or closed depends, of course, on the amount of movement imparted to the arm 32 by the rod 4. The greater the amount of rotation imparted to the rod 4, in the direction 10 to close the needle-valve and which is that of the encircling arrow, the wider the valve 29 is opened and the larger the exit from the passage 24 to the passages 28; and the greater the amount of rotation of said rod, in the opposite direction, the more nearly said valve 29 is closed and the smaller said exit becomes, until said last-named valve is completely closed and communication entirely cut off between said passages. 110

Tapped into the front end of the extension 24 is an elbow 34 arranged with one 115 120 125 130

terminal directed upwardly, and tapped into this terminal is a pipe 35. The pipe 35 extends upwardly from the elbow 34, and has its upper terminal (36, Fig. 5) introduced between the exhaust pipe 5 and the longitudinal central plane of the engine, and preferably in contact with said exhaust pipe. As clearly shown in Fig. 5, the terminal 36 is open and shaped to conform generally to the contour of the outer surface of the exhaust pipe 5, but must not fit said pipe so snugly as to prevent the entrance of air into such terminal. If desired, the edges of the terminal 36 may be serrated, in order to enable air to enter the pipe 35 in sufficient volume. When the valve 29 is open, hot air from the exterior of the exhaust pipe 5 is sucked into the terminal 36 and passes through the pipe 35 and the elbow 34 into the passage 24 where it may be retarded to a greater or less extent, according to the position of said valve, and onward to the manifold 1, through the intervening passages and openings. The hot air is drawn in by the suction of the pistons of the engine.

The size of each orifice 21 may be increased or decreased by adjusting the associated screw 18 out or in, thus limiting or regulating the maximum volume of hot air that can escape from the passage 22 above said orifice into the passage in the tube 10 in which said orifice is located.

Although the operation of this hot-air supply device as a whole will be generally understood from the foregoing description, a brief explanation of the same is given below.

When the arm 32 is disposed by the rod 4 in the position illustrated in Fig. 3, the valve 29 is in closed position, but the needle-valve is wide open or at least in position to admit a comparatively large volume of liquid fuel into the carburetor 2. Upon partially rotating the rod 4, in the direction of the encircling arrow, to decrease the aforesaid volume of fuel, the valve 29 is opened, through the medium of the arm 32, the spring 33, and the valve-stem 30, to permit hot air from outside of the exhaust pipe 5 to be sucked in, through the pipe 35, the elbow 34, the passages 24, 28, and 20, the orifices 21, the tubes 10, the orifices 14, and the slots 9 and openings 8 in the gasket 7, to the manifold 1. The hot air enters the opening 8 laterally from approximately diametrically opposite directions, so that the necessary balance is obtained and maintained, and said air intermingles to the best advantage with the combustion mixture which is being drawn into the manifold 1 from the carburetor 2. The combustible mixture is thus heated by the hot air, with the result that a greatly improved and more highly combustible mixture is delivered to

the cylinders of the engine, and less liquid fuel is needed and consumed. Since less liquid fuel is needed, the needle-valve of the carburetor can be more nearly closed than would be the case in the absence of the hot air supplied by means of my attachment, wherefore is effected the saving in fuel, and with this are attained greater engine power and speed, due to the improved mixture finally delivered to the cylinders. As the rod 4 is manipulated from time to time to increase or decrease the flow of liquid fuel, the valve 29 is correspondingly actuated to increase or decrease the volume of the supply of hot air from the exhaust. When the rod 4 is turned on its axis to close the needle-valve as far as its permanent adjustment permits, the valve 29 is opened wide, but this is of no particular importance.

Although the attachment is designed more especially for machines of the Ford type, it may be adapted for other types of machines.

More or less change in the shape, size, construction, and arrangement of some or all of the parts of this device may be made, without departing from the spirit of my invention or exceeding the scope of what is claimed.

What I claim as my invention, and desire to secure by Letters Patent, is—

1. The combination, in an attachment of the class described, with the carburetor and manifold and the exhaust pipe of an engine, of a distributor communicating with the interiors of said carburetor and manifold at approximately diametrically opposite points, and a pipe in open communication at one end with said distributor, and open at the other end, said last-named open end being placed against the outside of said exhaust pipe, and the edges of the opening in said last-named end being irregular so as to leave spaces between the same and said exhaust pipe.

2. The combination, in an attachment of the class described, with a carburetor, an inlet manifold, and a coupling between said carburetor and manifold, which coupling has approximately oppositely-disposed end portions that project beyond said carburetor and manifold, of independent tubular members connected with said projecting-end portions, and opening through said coupling into said manifold, a distributor mounted on said tubular members and having therein a passage to receive hot air from the outside of an exhaust pipe, and passages communicating with said first-named passage and with said tubular members, a valve to control the escape of said air from said first-named passage, and operating means for said valve.

3. The combination, in an attachment of the class described, with a carburetor, an inlet manifold, and a coupling between said

- carburetor and manifold, which coupling has approximately oppositely-disposed end portions that extend beyond said carburetor and manifold, of independent tubular members
- 5 5 connected with said projecting-end portions, and opening through said coupling into said manifold, a distributor mounted on said tubular members and having therein a passage to receive hot air from the outside of
- 10 the exhaust pipe, and passages communicating with said first-named passage and with said tubular members, a valve to control the escape of said air from said first-named passage, means for operating said valve, and
- 15 15 adjustable members arranged in said tubular members to regulate the entrance of the hot air from said distributor into said tubular members.
4. In an attachment of the class described,
- 20 20 a distributor having therein lower transverse openings for the reception of tubular members, hot-air-receiving and valve-receiving passages which are in line with each other and parallel with the axes of said
- 25 25 openings, and passages which extend outwardly and downwardly to connect said hot-air-receiving passage with said openings.
5. The combination, in an attachment of
- 30 30 the class described, with a carburetor and an inlet manifold, both having perforated coupling flanges, and a gasket receivable between said flanges, said gasket having therein a large central opening and slots extending outwardly from said opening, of tubular
- 35 35 members receivable in the perforations in said flanges and in said slots, and opening laterally into the latter, and means to secure said tubular members in place and bind said flanges and gasket together.
- 40 40 6. The combination, in an attachment of the class described, with a coupling between a carburetor and inlet manifold, provided with approximately diametrically opposite passageways opening into the passage in
- 45 45 said manifold, and an exhaust pipe, of tubular members connected with said coupling at approximately diametrically opposite points and opening into said passageways, a distributor mounted on said tubular mem-
- 50 50 bers and having therein passages which open into said members and other passages which open into said first-named passages, a tubular connection leading from one of said last-named passages to the exterior of said exhaust pipe, but not penetrating the same, a valve arranged in said distributor to open and close the passage into which said tubular connection opens, an operating means for said valve.
- 55 55 7. The combination, in an attachment of the class described, with a coupling between a carburetor and inlet manifold, provided with approximately diametrically opposite passageways opening into the passage in
- 60 60 said manifold, and an exhaust pipe, of tubu-
- lar members connected with said coupling at approximately diametrically opposite points and opening into said passageways, a distributor mounted on said tubular members and having passages therein which open into said members and other passages which open into said first-named passages, a tubular connection leading from one of said last-named passages to the exterior of said exhaust pipe, but not penetrating the same, a valve arranged in said distributor to open and close the passage into which said tubular connection opens, a spring arranged normally to maintain said valve in its closed position, and means to open said valve.
- 70 70 8. The combination, in an attachment of the class described, with the coupling between a carburetor and inlet manifold, provided with approximately diametrically opposite passageways opening into the passage in said manifold, and an exhaust pipe, of tubular members connected with said coupling at approximately diametrically opposite points and opening into said passageways, a distributor mounted on said tubular members and having passages therein which open into said members and other passages which open into said first-named passages, a tubular connection leading from one of said last-named passages to the exterior of said exhaust pipe, but not penetrating the same, a valve arranged in said distributor to open and close the passage into which said tubular connection opens, a spring arranged normally to maintain said valve in its closed position, and means to open said valve.
- 75 75 9. The combination, in an attachment of the class described, with laterally-extending perforated flanges at adjacent ends of a carburetor and an intake manifold, a gasket centrally perforated and longitudinally slotted to register with the passages in said carburetor and manifold and the perforations in said flanges, and an exhaust pipe, of tubes inserted in said perforations and the slots in said gasket, and having orifices therein to open into said slots, means to secure said tubes to said flanges and to bind said flanges and gasket together, a distributor mounted on said tubes and having therein passages which open into said tubes and other passages which open into said first-named passages, a tubular connection leading from one of said last-named passages to said exhaust pipe outside of the same, a valve arranged in said distributor to open and close the passage into which said tubular connection opens, and operating means for said valve.
- 80 80 10. The combination, in an attachment of the class described, with the coupling between a carburetor and inlet manifold, provided with lateral passageways opening into
- 85 85 90 95 100 105 110 115 120 125 130

- the passage in said manifold, orificed tubes connected with said coupling and opening through certain of the orifices into said passageways, a distributor mounted on said 5 tubes, and having therein passages which open into said tubes through certain others of said orifices, and other passages which open into said first-named passages, a tubular connection leading from one of said last-named passages to the exterior of said exhaust pipe, a valve arranged in said distributor to open and close the passage into which said tubular connection opens, and operating means for said valve. 10
11. The combination, in an attachment of the class described, with laterally-extending perforated flanges on adjacent ends of a carburetor and an intake manifold, a centrally-perforated and longitudinally-slotted gasket between said flanges, with the perforation therein registering with the passages in said carburetor and manifold, and the slots therein registering with the perforations in said flanges, and an exhaust pipe, 15 of tubes the rear terminal portions of which are introduced into the perforations in said flanges and pass through said slots, and orifices therein to open into said slots, said tubes being shouldered to abut the manifold flange, and said terminal portions being externally screw-threaded, nuts on the screw-threaded parts behind the carburetor flange, a distributor mounted on the forward terminal portions of said tubes, the latter being 20 shouldered to form abutments for said distributor behind, and internally screw threaded at their forward ends, adjusting screws in said ends, nuts on said screws to abut the front side of said distributor, said tubes 25 having therein orifices adjacent to said screws, and said distributor having therein passages which open into said last-named orifices, and other passages which open into said first-named passages, a tubular connection leading from one of said last-named 30 passages to said exhaust pipe outside of the same, a valve arranged in said distributor to open and close the passage into which said tubular connection 35 opens, said valve having a stem, a rotatable rod provided with an arm, and a spring connecting said arm with said stem. 40
- 45
- same, a valve arranged in said distributor to open and close the passage therein into which said tubular connection opens, and operating means for said valve. 50
12. The combination, in an attachment of the class described, with laterally-extending perforated flanges on adjacent ends of a carburetor and an intake manifold, a centrally-perforated and longitudinally-slotted 55 gasket between said flanges, with the perforation therein registering with the passages in said carburetor and manifold, and the slots therein registering with the perforations in said flanges, and an exhaust pipe, 60 of tubes the rear terminal portions of which are introduced into the perforations in said flanges and pass through said slots, and orifices therein to open into said slots, said tubes being shouldered to abut the manifold 65 flange, and said terminal portions being externally screw-threaded, nuts on the screw-threaded parts behind the carburetor flange, a distributor mounted on the forward terminal portions of said tubes, the latter being 70 shouldered to form abutments for said distributor behind, and internally screw threaded at their forward ends, adjusting screws in said ends, nuts on said screws to abut the front side of said distributor, said tubes 75 having therein orifices adjacent to said screws, and said distributor having therein passages which open into said last-named orifices, and other passages which open into said first-named passages, a tubular connection leading from one of said last-named 80 passages to said exhaust pipe outside of the same, a spring-pressed valve arranged in said distributor to open and close the passage into which said tubular connection 85 opens, said valve having a stem, a rotatable rod provided with an arm, and a spring connecting said arm with said stem.
